UNITED STATES PATENT OFFICE.

JOHN EDWARD OGDEN, OF MOUNTAINVILLE, NEW YORK.

BOLT-ANCHORAGE AND METHOD OF FORMING SAME.

1,367,080.

Specification of Letters Patent.

Patented Feb. 1, 1921.

Application filed July 24, 1920. Serial No. 398,742.

To all whom it may concern:

Be it known that I, JOHN EDWARD OGDEN, a citizen of the United States of America, and a resident of Mountainville, town of 5 Cornwall, Orange county, and State of New York, have invented certain new and useful Improvements in Bolt - Anchorages and Method of Forming Same, of which the following is a specification, reference being 10 had to the accompanying drawing, forming a part thereof.

This invention relates to anchorages for bolts or screws in materials with which the threads of the same cannot form a secure 15 engagement, and its object is to provide a simple, inexpensive and effective anchorage for this purpose, and a novel method of forming such an anchorage.

These and other objects of the invention 20 will appear in the specification which I will now proceed to describe and the novel features of which will be set forth in appended claims.

Referring to the drawing:

25 Figure 1 is a sectional elevation of a part of a member in which an anchorage is to be formed, with a bolt therein and certain anchorage elements shown in section surrounding the shank of the bolt.

30 Fig. 2 shows the same parts in the positions they assume after the anchorage has been formed. These figures illustrate a simple embodiment of this invention.

Fig. 3 is a sectional elevation of a modification of the form of some of the anchorage elements, and a full elevation of a forming tool which may be used to expand them.

35 Fig. 4 is a sectional elevation of an anchorage which has been formed of and by 40 the parts shown in Fig. 3, with a bolt partly screwed into it.

Fig. 5 is a sectional elevation of an anchorage and a nut which anchorage has been formed in accordance with this invention 45 together with a bolt shown in full elevation.

Figs. 6 and 7 are each end views and sectional elevations of anchorage members of different forms which may be used in carrying out this invention.

50 Like characters of reference designate corresponding parts in all the figures of the drawing.

55 10 designates a wall or other structure in which the anchorage is to be formed, and 11 is a hole drilled therein.

When the anchorage is to be formed in the manner illustrated in Figs. 1 and 2, a bolt 12 is inserted in the hole with the head thereof innermost. The shank of the bolt is then surrounded by a plurality of flat hard 60 metal washers 13 and a plurality of transversely bent washers 14 of soft or deformable material. The latter are preferably thicker than the flat washers. Then a nut 15 is screwed onto the bolt. The effect of 65 the longitudinal movement of the nut on the bolt will squeeze these anchorage members 13 and 14 together until they assume the positions in which they are shown in Fig. 2. As the bent washers become flattened thereby, their outside diameters have a tendency 70 to increase and this forces the material thereof against the wall of the hole 11 and thereby forms a secure anchorage. This effect is produced by a toggle effect in that 75 the openings in the deformable washers are only large enough to form a clearance with the shank of the bolt so that in flattening them they have a tendency to be forced into engagement not only with the wall of the 80 hole but also with the shank of the bolt. When the deformable washers 14 are of soft ductile material, this material is forced both against the wall of the hole and against the shank of the bolt and it also has the ad- 85 ditional effect of being forced into any irregularities in the wall and any interstices between themselves and the flat washers.

After the anchorage has been thus formed, the nut 15 may be removed and any 90 other desired article screwed onto the bolt, or of course, any desired article may be interposed between the nut 15 and the adjacent washer before expansion is effected, if this is desired. 95

In Fig. 3 the deformable washers 14 are of the same shape and construction as those shown in Fig. 1, but in this case, the hard metal washers 13^a are also bent transversely. Obviously anchorage members of 100 this kind can be expanded in the same way as that described in connection with Figs. 1 and 2. Another way of expanding them is shown in Fig. 3. A forming tool 20 has a shank 21 which extends through the apertures in the washers 14 and 13^a. This tool also has a part 22 of larger diameter preferably than that of the hole 11. The anchorage members can be flattened by applying pressure to the end of this tool 20, 110

as for example, by hammer bolts. In this case, the part 21 holds the anchorage members from being expanded inwardly beyond a desired extent, which is preferably about 5 the diameter of the base of the thread bolt which is to be used in the anchorage.

The apertures of the hard metal washers 13^a are of larger diameter than that of the part 21 of the forming tool, so that after 10 the anchorage has been formed and the forming tool removed, as shown in Fig. 4, the washers 13^a will clear the outside diameter of the threads of the bolt 23, but the bolt as it is screwed in, will cut threads 15 in the inwardly projecting parts of the soft metal washers 14. The part 21 of the forming tool is slidable within the part 22 so that these parts telescope together during the formation of the anchorage.

20 An anchorage formed of members like those shown in any of the preceding figures may be expanded in the way illustrated in Fig. 5, in which case a nut 25 is first inserted in the bottom of the hole and then a 25 bolt 26 surrounded by anchorage elements, such as 13 and 14, may be screwed into the nut to expand the anchorage element. In this Fig. 5 the anchorage has been formed and the bolt has been partly withdrawn 30 from the nut.

The deformable washers may be either dished, as shown in Figs. 1 and 3 or may be transversely bent in other ways such, for example, as that shown in Fig. 6, in which 35 the anchorage elements 14^a are curved differently. It is also within the scope of this invention to make the transversely bent anchorage elements as shown at 14^b in Fig. 7. The principle involved being that the diameters of the washers must increase when they 40 are flattened.

In a patent issued to Joseph Kennedy, No. 1,352,201, September 9, 1920, an anchorage is shown and described which is somewhat like 45 that of my invention, but I have discovered that it is not necessary in order to form an efficient anchorage to face deformable washers in opposite directions in order to obtain a double toggle grip, but that a single toggle 50 grip is also effected and can be obtained by the simple arrangement herein disclosed.

I have also found that a good anchorage may be formed of a plurality of flat washers by making some of them of hard metal and 55 some of soft metal, and then forcing them into a hole by longitudinal pressure applied to the outer member. In this case the soft metal washers are deformable in the sense that their thicknesses decrease during such 60 an operation and their outer diameter is increased and inner diameter decreased. During such an operation parts of the soft metal become forced into the interstices in the wall of the bore and the parts which are 65 extruded inwardly between the hard metal

washers fill in between the washers and also form an excellent surface for engaging the threads of an inserted bolt.

I have illustrated several forms of anchorage elements and different ways and means 70 of expanding them, to show that my invention is not limited to any specific form or way of expanding the elements except that the expansion must be made by applying longitudinal or end-wise pressure to the anchorage elements, and I intend no limitations other than those imposed by the appended claims.

What I claim is:

1. Means for forming an anchorage in an 80 aperture in a wall or other body comprising a plurality of washers every other one of which is transversely bent to reduce its external diameter, and means for flattening said bent washers within the aperture to increase the diameter thereof.

2. Means for forming an anchorage in an aperture in a wall or other body comprising a plurality of washers at least some of which are transversely bent to reduce their external 90 diameters, and placed with similar surfaces facing in the same direction, and means for flattening said bent washers within the aperture to increase the diameters thereof.

3. Means for forming an anchorage in an 95 aperture in a wall or other body comprising a plurality of alternate flat washers and washers transversely bent to reduce their external diameters, and means for flattening said bent washers within the aperture to increase the diameters thereof. 100

4. Means for forming an anchorage in an aperture in a wall or other body comprising a plurality of alternate flat washers and washers transversely bent to reduce their external diameters and to space the washers, and means for forcing said washers together. 105

5. Means for forming an anchorage in an aperture in a wall or other body comprising a plurality of washers every other one of 110 which is of soft metal transversely bent to reduce its external diameter, and means for flattening said soft metal washers within the aperture to increase the diameters thereof.

6. Means for forming an anchorage in an 115 aperture in a wall or other body comprising a plurality of alternating hard metal washers and soft metal washers, said soft metal washers being transversely bent to reduce their external diameters, and means for flattening said soft metal washers within the aperture to increase the diameters therof. 120

7. Means for forming an anchorage in an aperture in a wall or other body comprising a plurality of alternating hard metal washers and soft metal washers, said soft metal washers being transversely bent to reduce their external diameters, and means for flattening said soft metal washers within the aperture to increase the diameters thereof, 125 130

- the internal diameters of the hard metal washers being at least as great as the outside diameter of the threads of the bolt for which said anchorage is formed.
5. 8. The herein described method of forming an anchorage which consists of forming an aperture in a body, placing a plurality of alternate flat hard metal washers and soft metal washers therein, said soft metal washers being transversely bent to reduce their external diameters and to space the washers, forcing said washers together and expanding the soft metal washers by the application of longitudinal pressure and limiting the inward expansion of the soft metal washers while said pressure is being applied.
- 10 9. Means for forming an anchorage in an
- aperture in a wall or other body comprising a plurality of hard and soft metal washers, and means for forcing said washers together 20 by pressure applied thereto axially to thereby deform the soft metal washers.
10. Means for forming an anchorage in an aperture in a wall or other body comprising a plurality of alternately disposed hard and 25 soft metal washers, and means for forcing said washers together by pressure applied thereto axially to thereby deform the soft metal washers.

In witness whereof, I hereunto set my 30
hand this 22nd day of July 1920.

JOHN EDWARD OGDEN.

Witness:

I. B. MOORE.
